UNITED STATES PATENT OFFICE.

JOHN P. SCHILD, OF CLEVELAND, OHIO.

SELF-CLOSING FAUCET.

1,273,931.

Specification of Letters Patent. Patented July 30, 1918.

Application filed July 2, 1917. Serial No. 178,112.

To all whom it may concern:

Be it known that I, JOHN P. SCHILD, a citizen of the United States, residing at Cleveland, in the county of Cuyahoga and State of Ohio, have invented a certain new and useful Improvement in Self-Closing Faucets, of which the following is a full, clear, and exact description.

This invention relates to self-closing faucets; and is in the nature of an improvement on the faucet which is shown and described in the Rice Patent No. 804,673. The construction shown in that patent is practically efficient; but, after it has been in use for some time, the valve, in closing frequently goes against its seat with a thump; and likewise the valve frequently chatters before it finally becomes seated.

The object of this invention is to provide a faucet of the general character shown in the above mentioned patent, but which is so constructed that the valve will always go noiselessly to its seat without any thump or chattering.

To that end the invention consists in the construction and combination of parts shown in the drawings and pointed out definitely in the appended claims.

In the drawings, Figure 1 is a side elevation partly in central vertical section of a faucet which embodies this invention; Fig. 2 is a vertical section of the cap and valve operating stem, the section being in a plane at right angles to the plane of the section shown in Fig. 1. Fig. 3 is a side elevation of the assembly of the valve and water distributor plug, the plug being shown in section; Fig. 4 is a side elevation of the valve and water distributor plug assembly; Fig. 5 is an elevation sectioned at its lower end of the valve and valve stem; Fig. 6 is an elevation of the water distributor plug, the same being shown at right angles to the position in which it is shown in Fig. 4; Fig. 7 is a sectional view of a modified form of the valve and its stem.

Referring to the parts by reference characters, 10 represents the faucet casting containing a vertical cylindrical chamber 12, which is open at its top, and to which there is a water inlet 13 near its bottom, and from which there is a laterally extended water outlet 14 above the water inlet. Between

the inlet and outlet this chamber contains an annular shoulder 12^a. 55

In this central chamber 12, a water distributing plug 15 is fitted. Adjacent its lower end this plug is of slightly reduced diameter, thereby leaving the annular downwardly faced flange 15^a which rests upon the shoulder 12^a, there being the packing ring 16 interposed between these two surfaces. A cap 18 is screwed down into the open upper end of the chamber 12 to close the same; and it engages the upper end of the plug and 60 forces it down whereby the water tight joint is formed between the surfaces 12^a and 15^a with the aid of said packing ring 16.

The water distributing plug 15 has a centrally placed cylindrical hole 15^b extending 70 through it from top to bottom. It has an annular valve seat 15^c on its lower end around this hole. This hole is enlarged at its upper end to form a recess 15^d in which packing 17 is placed. Packing rings 19 rest 75 upon the top of the plug and upon the packing in said recess; and it is against the upper of these packing rings that the lower end of the screw cap 18 directly engages.

A portion of the outer part of this plug is 80 cut away clear to the central hole 15^b, as at 15^e, whereby a water passageway is formed; and this cut away portion is so located that the produced water passageway is in communication with the outlet 14; wherefore 85 any water which comes into the inlet 13, and goes up through the hole 15^b will pass through this water passageway to the outlet 14. A cylindrical valve stem 20 passes through the hole 15^b in this water distributing plug from top to bottom, and has a nice sliding fit therein. A valve disk 21 is fixed to the lower end of this valve stem for engagement with the valve seat 15^c. This valve stem is formed with a water passage 90 way 20^a, the lower inlet end of which is at a distance of approximately one quarter of an inch above the valve disk; and its discharge end is at a point such that it will communicate with the water passage formed by the cutting away of the plug at 15^e as above explained. In the construction which has given the most practical satisfaction this water passageway 20^a is a groove cut spirally in the external surface of the valve 95 stem, as shown in Figs. 1, 3, 4 and 5.

But the device will operate satisfactorily if the valve stem be constructed as shown in Fig. 7. As therein shown the water passageway consists of a longitudinal hole 20^b, 5 formed in the valve stem and provided with a lateral inlet 20^c placed at about the same distance above specified above the valve 21, and a lateral outlet 20^d so placed that it will communicate with said water passage around 10 the plug when the valve is opened.

To cause water to flow through this faucet the valve stem is pushed down, by means which will be presently explained; or some other suitable means; and it is pushed down 15 far enough to uncover the lower inlet end of the water passageway carried by the valve stem. So long as the valve is so held down, water will flow into said water passageway from below the plug, and will 20 be discharged into the water passageway around the plug, and thence to the outlet 14. When the pressure holding the valve open, as stated, has been released the water pressure below the valve will force said valve 25 upward. There can be no lateral movement of the valve because the stem thereof has a nice sliding fit in the hole in the plug. When the valve 21 comes to within approximately one quarter of an inch of the valve seat 15^d, 30 the lower end of the water passageway carried by the valve stem will be substantially closed by the wall of the hole through the plug 15. Then the valve will slowly move upward the remaining distance until it seats 35 itself noiselessly and without any possibility of chattering against the valve seat 15^d.

The means shown for pushing this valve stem downward consists of a stem 24 which is rotatably fitted in a hole in the top of the 40 cap 18, and it has a handle 26 secured to its upper end. On its lower end, within a recess 18^a in the lower end of the cap, this stem is provided with a laterally extended head 25 having oppositely inclined upper faces 45 25^a, which will engage with correspondingly inclined surfaces 18^b carried by the cap within this recess 18^a. Therefore, by turning this operating stem 24, it will be caused to move downward. It is always in engagement with the upper end of the valve stem, 50 and will therefore cause the valve stem to move downward with the results above pointed out.

Having described my invention, I claim:—

55 1. A self-closing faucet having a vertical chamber which is provided with an inlet adjacent its lower end and a laterally extended outlet between its ends, a plug fitted within said chamber and extending both 60 above and below the water outlet, said plug having a vertical cylindrical hole through it from top to bottom and having a laterally extended passageway from said hole to said chamber in the plane of the water outlet 65 therefrom, and said plug having an annular

valve seat on its lower end, a vertical valve stem which is nicely fitted to and is slidable within the vertical hole in said plug and extending both above and below the same, and having on its lower end a valve for engagement with said valve seat,—and said stem being provided with a water passage which at its upper end is in communication with the lateral water passage in the plug and which at its lower end terminates in a part 70 of the surface of said valve stem, which is such a distance above the valve that it may be uncovered by the downward movement of the valve from its seat, but which will pass wholly within said hole and be entirely 80 covered so as to stop the entry of water into the same before the valve in closing comes in contact with its seat, and means for pushing said valve stem downward.

2. A self closing faucet having a vertical 85 chamber which is provided with an inlet near its lower end and a lateral outlet between its ends, a water distributing plug fitted in said chamber and extended both above and below the outlet therefrom, said 90 plug having a valve seat on its lower end and having a vertical cylindrical hole through it from top to bottom and a water passage leading from said hole to said chamber adjacent the outlet from said chamber, 95 a cylindrical valve stem which is nicely fitted to and is slidable in the hole in said plug and which has an external spiral groove which extends from a point a short distance above the valve such that as the 100 valve is closing this lower end will pass wholly into the hole in the plug and be closed thereby before the valve reaches its seat to a point where it will communicate with the lateral water passage of the plug 105 when the valve stem has been pushed down far enough to uncover the lower end of said groove, a valve disk fixed to the lower end of said valve stem, and means to force said valve stem downward.

3. A self-closing faucet having a vertical 110 chamber which is provided with an inlet near its lower end and a lateral outlet between its ends, a water distributing plug fitted in said chamber and extending both 115 above and below the outlet therefrom and having a valve seat at its lower end, a vertical hole through it from top to bottom which hole is enlarged at its upper end for the reception of packing and said plug also having a lateral water passage leading from said hole to said chamber adjacent the outlet therefrom, a valve stem slidably fitted in the hole in said plug and having on its lower end a valve for the engagement of said 120 valve seat and said stem being provided with a water passage which terminates at its lower end a slight distance above the valve and at its upper end at a point where it will communicate with the lateral water passage 125 130

in the plug when the valve stem has been pushed downward far enough to uncover the lower end of said water passage, packing in the enlarged recess in the upper end 5 of said plug, a metal packing ring on top of said plug and extending over said packing, a cap which screws into the upper end of said chamber and bears upon the packing

ring, and means carried by said cap to force said valve stem downward. 10

In testimony whereof, I hereunto affix my signature.

JOHN P. SCHILD.
